LAUNDRY APPARATUS.

(Application filed May 26, 1899.)

(No Model.)

A detailed technical line drawing of a mechanical assembly, likely a cylinder or valve. The drawing shows a main body with various parts labeled with numbers. Labels include: 26, 24, 27, 29, 30, 23, 37, 25, 20, and 39. The assembly consists of a long horizontal tube with a vertical support and a complex internal mechanism.

UNITED STATES PATENT OFFICE.

WILLIAM HENRY WELSH, OF STILLWATER, MINNESOTA.

LAUNDRY APPARATUS.

SPECIFICATION forming part of Letters Patent No. 640,847, dated January 9, 1900.

Application filed May 26, 1899. Serial No. 718,381. (No model.)

To all whom it may concern:

Be it known that I, WILLIAM HENRY WELSH, a citizen of the United States, residing at Stillwater, in the county of Washington and State of Minnesota, have invented certain new and useful Improvements in Laundry Apparatus, of which the following is a full and complete specification, such as will enable those skilled in the art to which it appertains to make and use the same.

This invention relates to drying apparatus for use in laundries; and the object thereof is to provide an improved apparatus of this class which comprises a suitable main frame or support and a plurality of drying-frames which are adapted to be connected with said main frame or support and to be held in an upright position and to be successively released and allowed to fall into a horizontal position; and with this and other objects in view the invention consists in the construction, combination, and arrangements of parts hereinafter described and claimed.

The invention is fully disclosed in the following specification, of which the accompanying drawings form a part, in which the separate parts of my improvement are designated by the same numerals of reference in each of the views, and in which—

Figure 1 is a front elevation of the apparatus which I employ, a number of the drying-frames being shown in position; Fig. 2, a plan view thereof; Fig. 3 a side view, and Fig. 4 a perspective view, of the drying-frames detached from the main frame or support of the apparatus and suspended on horizontal wires or other supports, the main portion of the drying-frames only being shown.

In the practice of my invention I provide a plurality of drying-frames which consist each of side plates 5 and outer and inner end bars 6 and 7, and connected with said side plates and said end bars are longitudinal and transverse wires or strands 8 of any suitable material. The outer end bars 6 are provided at each end with hook-shaped catches 9, the purpose of which is hereinafter described, and in the practice of my invention I assemble a number of the drying-frames composed of the members 5, 6, and 7 and cross-wires 8, each of which frames is connected by means of keepers 10, secured to the end bars 7 at

either end thereof and within the side plates 5 and with a loop of a helical spring 11, three of the said drying-frames being shown so assembled in the drawings. 55

Two of the springs 11 are employed, and each of the ends of each is connected with a head 12, and the springs are retained in parallel position and the heads connected in pairs 60 by means of normally parallel brace-rods 13 and 14, respectively, and the ends of the brace-rod 13 are provided with angular end projections 15 and the brace-rod 14 with angular end projections 16, adapted to engage 65 therewith to lock the springs 10 in compressed position, and in practice the collars and cuffs to be dried are laid upon the frames 5, 6, 7, and 8 and then dried, as hereinafter described. 70

I also provide a main frame or holder for the drying-frames, comprising a base 17, centrally of which is supported an upwardly and slightly rearwardly directed support 18, and on either side of said support are a pair of 75 uprights 19, inclined similarly thereto, and connected with one end of the base 17 and extending at right angles thereto is a supplemental base 20, from the forward end of which projects an upwardly-directed yoke-shaped support 21, provided at its upper end with two arms 22 and 22^a, the first of which is bifurcated, forming a supplemental yoke-shaped support, comprising arms 23 23. The main frame or support is also provided with 80 devices for supporting and releasing the drying-frames, which I will now describe. A lever-arm 24, provided with a handpiece 25 at its forward end, is pivoted to the rear end of the base 20, as at 26, and a keeper 27 is secured to the base 20, and the forward end of the lever 24 operates within the same and is actuated by a coiled spring 28, mounted between said lever and the base 20. 90

A double-crank lever 29 is pivoted between the arms 23 by means of a pin 30 passing through one of its arms 31, and pivoted at the outer end of its other arms 32 and 33, as at 34 and 35, respectively, are a pair of angular fingers 36 and 37, respectively, and said fingers project through and operate within horizontally-arranged perforations 38 in the inner arm 22^a of the yoke-shaped support 21. 95

A link-rod 39 is pivotally connected with

the double-crank lever 32, and is also connected with the lever-arm 24, centrally thereof, and if when the parts are arranged as shown in the drawings the handpiece 25 be depressed the finger 36 will be projected through its opening 38 and the finger 37 correspondingly withdrawn, and when the handpiece 25 is released the opposite movement of said parts will ensue.

- 10 When it is desired to dry the collars and cuffs which have been spread upon the drying-frame, the latter are suspended from wires, comprising an upper parallel pair 40 and a lower parallel pair 41, in the position 15 shown in Fig. 4. The springs 11 are allowed to expand, forcing apart the brace-rods 13 and 14, and the inner ends of the frames are placed upon the lower wires 41, and the catches 9 are hooked over the upper wires 40 20 and the frames allowed to rest in an inclined position.

In the practice of my invention the main frame or holder is placed upon a table or other support, and the projections 15 and 16 25 of the brace-rods 13 and 14 of the springs 11 are brought into engagement, compressing said springs and bringing the inner ends 7 of the drying-frames into a bunched position, as shown in Figs. 1, 2, and 3. The uprights 30 19 are then passed upward between the projections 15 and 16 and the frame inner ends 7, and the frames are raised and held in such position by the fingers 36 and 37, as shown in the drawings, and are prevented from falling 35 rearwardly by the support 18.

In the position described the fingers 36 and 37 project approximately entirely across the adjacent side plate 5, as shown in Fig. 1, and when it is desired to fill one of the drying-40 frames the handpiece 25 is depressed and allowed to rise under actuation of the spring 28, and by this action one of the said frames will fall, as shown in Fig. 3. The motion of the fingers 36 and 37 is alternately reciprocating through the openings 38, and the result thereof is to pass the frames forwardly to the finger 37. When all the drying-frames 45 have been filled, they are detached from the uprights 19 and carried to the drying-room, 50 where they are separated into the position shown in Fig. 4, the projections 15 and 16 of the end rods 13 and 14 being taken out of engagement and the springs 11 expanded, and said frames are suspended from the wires 40 and 41, as shown in Fig. 4. The springs 11 55 are also retained in their extended position by means of cords or other devices 42, attached to the heads 12 and suitably secured adjacent thereto, and when the collars and cuffs are 60 dried the cords 42 are detached and the frames removed from the wires 40 and 41, and the collars and cuffs may be slid therefrom and finished as usual.

It will be apparent that any desired number 65 of the drying-frames may be connected and operated as herein shown and described, and the entire apparatus is simple in construc-

tion and operation and well adapted to accomplish the result for which it is intended, and it will be apparent that changes in and modifications of the construction herein described may be made without departing from the spirit of my invention or sacrificing its advantages.

Having fully described my invention, I claim as new and desire to secure by Letters 75 Patent—

1. In an apparatus of the class described, a main frame or support, a plurality of flexibly-connected portable drying-frames which are adapted to be detachably mounted on said 80 main frame or support, and devices for holding said frames in an upright position, and for releasing the same one at a time, substantially as shown and described.

2. In an apparatus of the class described, 85 a plurality of drying-frames, flexibly connected at one end, and devices for locking said connected ends in a bunched position, substantially as shown and described.

3. In an apparatus of the class described, 90 a main frame or support, a plurality of drying-frames flexibly connected and adapted to be held in a bunched position on said frame or support, said frame or support being also provided with a pair of reciprocating fingers, and 95 adapted to engage said frames to hold them in a raised position, and to successively release said frame, substantially as shown and described.

4. In an apparatus of the class described, 100 a main frame or support, and a plurality of drying-frames flexibly connected at one end, said main frame or support being also provided with an upwardly-directed member, and uprights at each side thereof which engage 105 said drying-frames, and said main frame or support being also provided with reciprocating fingers adapted to operate in connection with said drying-frames to hold the same in an upright position, and also to successively 110 release them, substantially as shown and described.

5. In an apparatus of the class described, 115 a main frame or support, and a plurality of drying-frames flexibly connected at one end, 120 said main frame or support being also provided with an upwardly-directed member, and uprights at each side thereof which engage said drying-frames, and said main frame or support being also provided with reciprocating 125 fingers adapted to operate in connection with said drying-frames to hold the same in an upright position, and also to successively release them, and a pivoted spring-operated lever in operative connection with said fingers, substantially as shown and described.

6. In an apparatus of the class described, 130 a main frame or support, a plurality of drying-frames flexibly connected at one end, means for connecting said drying-frames with said main frame or support, and a pair of reciprocating fingers mounted in said main frame or support and adapted to hold said drying-frames in an upright position, and also

to successively release the same, substantially as shown and described.

7. In an apparatus of the class described, a main frame or support provided with a bifurcated arm, a double-crank lever pivoted in said arm, two angular fingers pivotally connected with said crank-lever, and a plurality of drying-frames flexibly connected at one end, and also adapted to be connected with said main frame or support, said drying-frames being adapted to be held in an upright position, and to be successively released by said fingers, substantially as shown and described.

15 8. In an apparatus of the class described, a yoke-shaped support, one of the arms of which is bifurcated, a double-crank lever pivoted in said support by one of its arms, an angular finger pivotally connected with each of the other arms of said crank-lever, and a piv-

oted spring-operated actuating-lever operatively connected with said double-crank lever, substantially as shown and described.

9. In an apparatus of the class described, a plurality of drying-frames, a pair of coiled springs with the convolutions of which said frames are pivotally connected, heads secured to the ends of said drying-frames, and brace-
25 rods connected with said heads and provided with end projections adapted to engage, substantially as shown and described.

In testimony that I claim the foregoing as my invention I have signed my name, in presence of the subscribing witnesses, this 22d day of May, 1899.

WILLIAM HENRY WELSH.
